ORGAN PIPE COMPANY, OF READING, MASSACHUSETTS, A CORPORATION OF MASSA-
CHUSETTS.

PLUG FOR ORGAN-PIPE FEET.

1,331,258.

Specification of Letters Patent.

Patented Feb. 17, 1920.

Application filed March 26, 1919. Serial No. 285,307.

To all whom it may concern:

Be it known that I, EDWIN B. HEDGES, a citizen of the United States of America, and a resident of Westfield, in the county of 5
Hampden and State of Massachusetts, have invented a new and useful Plug for Organ-Pipe Feet, of which the following is a specification.

My invention relates to improvements in 10
adjustable regulating devices for the air which passes through the feet of organ pipes, and consists of a metallic screw-plug tapped into and through one side of such a foot, and provided with means for engaging therewith a wrench or other tool or implement for the purpose of turning such plug in or out, all as hereinafter set forth.

This plug is intended more especially for 20
the foot of a manual organ pipe. The manual feet extend through the rack-board and stand on top of the wind-chest of the organ, said feet extending some five inches below the top of said board. Any air-regulating device for these feet, if adjustable, must be accessible above the aforesaid 25
rack-board. Furthermore, the unoccupied space around said feet is so limited that no considerable projection from the feet is practicable if possible, wherefore the means 30
for adjusting the plugs must not occupy or require much space. One object of my invention, therefore, is to provide plugs for organ-pipe feet, and especially for the feet of manual pipes, which plugs are capable 35
of being and adapted to be adjusted in the space available for such operation.

The pipes to which this invention 40
pertains are made of wood which, as a matter of course, swells and shrinks under different atmospheric conditions. And another object is to provide a plug which, not only can be adjusted to advantage and with the greatest degree of accuracy, for the purpose of permitting with exactitude the correct volume of air to pass through the foot 45
that is equipped with such plug, but is not itself appreciably affected by atmospheric conditions, and is practically unaffected by any changes that the wood of said foot may 50
undergo as the result of such conditions.

Other objects and advantages will appear in the course of the following description.

I attain the objects and secure the advantages of my invention by the means illus-

trated in the accompanying drawings, in which—

Figure 1 is what may be termed a front elevation of an organ-pipe foot which is equipped with a practical form of my plug; Fig. 2, a side elevation of said foot and gate; Fig. 3, a central, vertical section through such foot and plug; Fig. 4, a front elevation of another and smaller organ-pipe foot which is equipped with a slightly modified form of plug; Fig. 5, a side elevation of said last-named foot and plug; Fig. 6, a central, vertical section through the smaller foot, with its plug in elevation, and Fig. 7, a cross section through a smaller foot, the plug being left in elevation.

Similar reference numerals designate similar parts throughout the several views.

The feet of the pipes of an organ vary in size, like the pipes to which they are attached, and in the drawings I have shown 75
a foot 1 of the larger size, and a foot 11 of the smaller size. These feet are of wood and have passages 2 and 12, respectively, extending through them from end to end. A shoulder 3 is formed on the foot 1 a short 80
distance below the upper end thereof, and the foot 11 has a similar shoulder 13. It is the parts of the feet above the shoulders 3 and 13 which are received in the pipes of the organ, with said shoulders abutting the 85
bottom ends of said pipes.

Metallic plugs 4 and 14 are fitted to the feet 1 and 11, respectively, such plugs being located a little way below the shoulders 3 and 13, and projecting into the passages in 90
said feet. The axes of the plugs 4 and 14 are at right-angles to the axes of the feet 1 and 11, respectively.

The plug 4 is convex at its inner end, as represented at 5, and the body of said plug 95
is externally screw-threaded to engage an internally screw-threaded opening 6 in one side of the foot 1. Similarly the plug 14 has a convex inner terminal 15, and its body is externally screw-threaded to engage an 100
internally screw-threaded opening 16 in one side of the foot 11.

Each foot, 1 or 11, is annular in cross section, and each plug 4 or 14, is cylindrical in cross section, the former having the shape 105
of a hollow cylinder, as will presently more fully appear. The diameters of the plugs are less than the diameters of the passages

into which said plugs extend, as is clearly shown in the case of the plug 14 and the passage 12 in Fig. 7, it being understood that the same thing is true of the plug 4 and the passage 2.

It is now clear that either passage 2 or 12 may be choked to a greater or less extent by screwing in or out the plug which projects into such passage. But the plugs can 10 never completely close the passages into which they extend, even though they should be screwed in far enough to contact with the walls opposite to the openings 6 and 16, owing to the fact that the diameters of said 15 plugs are less than the diameters of said passages. The convex ends 5 and 15 permit the plugs to be advanced farther than would be the case if the inner ends of said plugs were flat, inasmuch as said convex 20 ends conform more or less closely to the concavities of the adjacent portions of the walls of the passages, consequently a greater range of adjustment is made possible. The 25 volumes of air that pass through the feet 1 and 11 are, of course, increased or decreased accordingly as the plugs 4 and 14 are adjusted to position them farther out or farther in, as will be plainly seen. In practice, each plug must be set to permit of the 30 passage through its foot of the required amount of air, being adjusted from time to time as may be necessary in order to obtain the best results.

The plugs 4 and 14 must not project too 35 far outside of the feet 1 and 11, for the reason previously given, wherefore it is necessary to provide means whereby they may be rotated for adjustment, with the aid of a wrench or other suitable implement that can 40 be introduced into the limited space available. To this end, therefore, the larger plug has an interior, integral cross-piece or web 7, and the smaller plug has an exterior, integral nut 17.

The plug is made hollow, a chamber 8 thus being provided which opens at the outer end of said plug. The web 7 is at the inner end of the chamber 8 and extends transversely across said chamber. The plug 45 is adjusted by introducing into the chamber 8 the jaws or equivalent members or member of a wrench or other implement and engaging the web 7 therewith, and by this means turning said plug in or out, accordingly as to whether it be desired to decrease

or increase the volume of air which passes through the foot 1, and to whatever extent it may be necessary in order properly to regulate such volume.

The larger plug is made hollow for the 60 purpose of saving metal and lightening the same. The smaller plug, owing to its size, must be made solid.

The nut 17 is at the outer end of the plug 14, and said plug is adjusted by means of 65 said nut, with the aid of a wrench or other implement which is adapted to engage said nut, in a similar manner to that in which the plug 4 is adjusted.

The plugs being of metal do not shrink 70 or swell, and being tapped into the feet have sufficient frictional engagement therewith to prevent them from becoming too loose and working out of place. Obviously the plugs can be adjusted with a great 75 degree of accuracy, and without fear that they will get out of adjustment.

I am aware that wood plugs have been provided to fit plain holes in organ-pipe feet, which plugs have exterior handles of 80 sufficient length to be grasped in the hand for adjustment purposes, and do not seek to claim such a plug. This old type of plug is not only defective because it is made of wood and has no screw-threaded engagement 85 with the foot, but is not available for the feet of manual organ-pipe feet, owing to the presence of the handle.

What I claim as my invention, and desire to secure by Letters Patent, is— 90

1. The combination, with a wooden organ-pipe foot, of a metallic plug tapped into and through one side of said foot, said plug having a convex inner end to cooperate with the inner surface of said foot, and 95 being provided with means which is accessible at the outer end for the engagement therewith of an adjusting implement.

2. The combination, with a wooden organ-pipe foot, of a metallic plug tapped 100 into and through one side of said foot, said plug having means accessible at the outer end for the application thereto of an adjusting implement, and being of less diameter than the passage which it intersects. 105
